(57) **CLAIM**

I claim the ornamental design for a range hood, as shown and described herein.

DESCRIPTION

FIG. 1 is a front elevational view of the range hood; and, FIG. 2 is a side elevational view of the range hood shown in FIG. 1, with the opposite side being a mirror image of the same.

The top and bottom of the range hood shown in FIGS. 1 and 2 form no particular part of the claimed design.

The characteristic feature of the claimed design resides in a series of panels positioned in the lower half of the front of the range hood as shown.
